UNITED STATES PATENT OFFICE.

WILLIAM C. HEDGCOCK, OF CHICAGO, ILLINOIS, ASSIGNOR TO AMERICAN STEEL
FOUNDRIES, OF NEW YORK, N. Y., A CORPORATION OF NEW JERSEY.

FORGED-STEEL FULCRUM.

1,202,839.

Specification of Letters Patent. Patented Oct. 31, 1916.

Application filed August 18, 1916. Serial No. 115,323.

To all whom it may concern:

Be it known that I, WILLIAM C. HEDGCOCK, a citizen of the United States, and resident of Chicago, in the county of Cook and State of Illinois, have invented certain new and useful Improvements in Forged-Steel Fulcrums, of which the following is a specification.

My invention relates to railway brakes and has particular reference to a novel brake beam construction and the means for supporting the same in operative position.

It is desirable in many instances to provide a third point support for brake beams 15 of the truss type and difficulty has been experienced in providing a means of connection between the brake beam strut and the supporting means. To this end, I have provided a forged steel strut composed of 20 a single piece of metal, which is doubled upon itself, the two ends of the piece of metal being secured to the channel-shaped compression member, whereas the other end of the member is shaped to provide a saddle 25 for the round rod tension member. In order to provide a support adapted for use in connection with an arrangement such as described, I have provided a clevis which is adapted to be secured to the strut by means 30 of a rivet which passes through a vertical aperture located at the tension member end of the strut. This forms an extremely economical means of connection to the third point support.

The invention will be more readily understood by reference to the drawings, wherein—

Figure 1 is a vertical section through a portion of a car truck showing the third point supporting means and the strut of the brake beam; Fig. 2 is an elevation of the clevis and its integral stem before being inserted in the strut; Fig. 3 shows a strut and clevis of a slightly modified form; Fig. 4 is an end view of the construction shown in Fig. 3, and Fig. 5 is a view similar to Fig. 3, showing a slight modification thereof.

In the construction of Fig. 1, it will be noted that the arch or spring supporting member 10, is secured at one end to the spring plank 11, the other end providing an eye by means of which a link 12 is supported. The lower end of the link is pivoted by means of a pin or rivet 13 to a clevis or bracket composed of two apertured lugs 14,

terminating in a stem or shank 15. This shank is adapted to enter a vertical aperture in the head end of a one piece forged fulcrum. This fulcrum comprises a single piece of metal, bent to provide two arms 16, 17. A saddle 18 is formed in one end to accommodate the tension rod 19 of the brake beam. The other end of the strut is connected by means of the ears 20 to the channel compression member 21. After the shank 15 has been inserted in the aperture, it is riveted over, as at 22.

In the construction shown in Figs. 3 and 4, the strut remains the same, the clevis being slightly modified. In this instance 70 it comprises a bar or strip of metal which is bent into U-shape, providing a flat portion 23, which lies against the strut and is apertured to accommodate the fastening rivet 24; the clevis is then bent to provide 75 two arched portions 25, 26, which terminate in apertured ears 27, 28, which serve to connect the third point support.

In the construction of Fig. 5, the strut likewise remains the same, the bracket or clevis comprising a flat strip 29, apertured to accommodate the rivets 30 at one end and doubled upon itself to provide the eye 31 at the other end, by means of which eye the third point supporting means are connected. 80

By reason of the construction shown, a simple and an economical form of connection is provided for a forged fulcrum and a third point supporting means, this being accomplished without weakening the strut and 90 without material increase in the cost of production.

I claim:

1. In a brake beam, the combination of a tension member, compression member and strut, said strut being composed of a single piece of metal forged to the required shape, and having a vertical aperture near one end thereof, third point supporting means, including a clevis and a rivet passing through 100 said aperture and securing said clevis in place.

2. In a brake beam, the combination of a tension member, compression member and strut, said strut being composed of a single 105 piece of metal forged to the required shape, and having a vertical aperture near the tension member end thereof, an arched supporting member above the beam, a clevis pivotally connected to said supporting member, 110

said clevis having an integral shank adapted to enter said aperture, substantially as described.

3. In a brake beam, the combination of a tension member, compression member and strut, said strut being composed of a single piece of metal forged to the required shape, and having a vertical aperture near the tension member end thereof, an overhanging 10 third point suspension including a clevis

and vertically disposed fastening means co-operating with said aperture and fastening said clevis to said strut, substantially as described.

Signed at Chicago, Illinois, this 11th day 15 of August, A. D. 1916.

WILLIAM C. HEDGCOCK.
